DESIGN FOR A RADIO CABINET

Hal G. Sherry, Pasadena, Calif.

Application May 10, 1947, Serial No. 138,964

Term of patent 3½ years

(Cl. D56—4)

To all whom it may concern:

Be it known that I, Hal G. Sherry, a citizen of the United States, residing at Pasadena, in the county of Los Angeles and State of California, have invented a new, original, and ornamental Design for a Radio Cabinet, of which the following is a specification, reference being had to the accompanying drawing, forming part thereof.

In the drawing the figure is a perspective view of a radio cabinet showing my new design.

I claim:

The ornamental design for a radio cabinet as shown.

HAL G. SHERRY.
